UNITED STATES PATENT OFFICE.

MURVIN C. DEIFENDERFER, OF BLUFFTON, OHIO, ASSIGNOR TO SCOTT & EWING COMPANY, A PARTNERSHIP COMPOSED OF FRANK SCOTT AND E. R. EWING, BOTH OF BLUFFTON, OHIO.

KEY-PULLING TOOL.

Application filed January 23, 1925. Serial No. 4,173.

To all whom it may concern:

Be it known that I, MURVIN C. DEIFENDERFER, a citizen of the United States, residing at Bluffton, in the county of Allen 5 and State of Ohio, have invented certain new and useful Improvements in Key-Pulling Tools, of which the following is a specification, reference being had therein to the accompanying drawing.

10 My invention relates to key pullers.

It is the object of my invention to provide a key puller which will grip the key with increasing force as the pull on the key is increased.

15 It is a further object of my invention to provide a key puller which is adjustable to different sizes of keys and which is adapted to have different sizes and types of key gripping surfaces substituted in the master key 20 pulling tool.

It is a further object of my invention to provide a tool which is adaptable for use on either a short shaft without the tool tilting or a long line shaft.

25 It is a further object of my invention to provide a tool having means for carrying the anti-tipping means of the tool when used with short shafts in a predetermined relationship with the rest of the tool despite 30 the movement of the tool with respect to the short shaft.

It is a further object to provide means for moving the key puller as a whole with the key relative to the shaft, means for adjusting the initial grip on the key, and means for adjusting the anti-tipping device associated with the key pulling tool.

It is a further object of my invention to provide a very rigid and sturdy tool of 40 simple construction which, even though the parts may wear, will not effect its operation as it is so adjustable as to compensate for wear.

Referring to the drawings:

45 Figure 1 is a plan view of the tool with the anti-tipping device in position and a key in the clamping jaws of the tool;

Figure 2 is an end elevation of the tool from the key end;

50 Figure 3 is an end elevation of the tool viewed from the end on which the screws are actuated;

Figure 4 is a section through the tool showing the tool applied to a short shaft and in the process of extracting a key from 55 said shaft;

Figure 5 is a side elevation of the tool without the anti-tipping device mounted on a long shaft such as a line shaft in the process of extracting a key;

Figure 6 is an end elevation from the actuating end with the shaft in section and the key in section showing the location and position of the tool without the anti-tipping device;

Figure 7 is a section on the line 7—7 of Figure 1;

Figure 8 is a section on the line 8—8 of Figure 1;

Figure 9 is a plan view of a pair of the 70 detachable clamping jaws showing a somewhat different form of jaws which are adaptable for such a tool.

Turning to the drawings and describing them in detail, 1 is a base block which carries the master actuating screw 2 which serves to move the entire tool relative to the shaft, thus extracting the key from the shaft as the key travels with the tool when suitably clamped as hereinafter described. This 80 shaft 2 is threaded in a threaded portion 3 on the base block 1. It turns freely in and is spaced from the base block 1 due to the enlarged apertures 4 and 5 on either side of the threaded portion 3 of the base block 85 1. The actuating end of this screw is squared at its edges to receive a suitable handle or crank or other agency for rotating the screw 6.

The other end of the screw is provided 90 with a head 7 having an annular depression 8. On this head is mounted a cup-shaped member 9 having a roughened face 10 for engaging with the hub or other portion of a member mounted on the shaft with the key. This cup-shaped detachable head is maintained in position on the head 7 of the screw by a set screw 11 which passes through the member 9 into the annular groove 8 of the head 7.

This base block is provided on either side with upwardly extending shoulders 12 which have spaced overhanging ledges 13. Such spaced overhanging ledges or shoulders may

be integral with the base block or mounted on there detachably through the agency of the countersunk screws 14. These overhanging portions are so arranged that their opposite faces 15 converge towards one another to the end of the tool as at 16. This portion of the tool has its outside faces 17 and 18 also tapering and converging towards the face 16. The faces 15 with the converging over-hanging ledges 13 and shoulders 12 form converging guide ways for the sliding triangular shaped blocks 19 which carry the clamping jaws 20. These blocks are provided with stems 21, the central axis of which is parallel with the outer diagonal face 22 of the block 19, which face rides against the tapering face 15 which guides it inwardly as the block proceeds outwardly. This stem 21 projects through a diagonally arranged aperture 23 formed in the head 24 which is mounted upon the base block 1. This head 24 is held in position by similar countersunk screws as those marked 14.

I prefer to make this head 24 integral with the overhanging shoulders and ledges so that a U-shaped member is thus formed which is inmounted on the base block 1. This U-shaped member has shouldered arms 12 which converge towards one another.

It will be obvious that the sliding blocks 19 will thus be guided so that as they move inwardly and outwardly with their inner faces 25 parallel to the major axis of the tool, such faces 25 will be approaching such major axis and approaching one another. Thus the clamping jaws 20 which have the roughened surfaces 26 will be forced in tighter and tighter engagement with the key 27 as the jaws change their position relatively to the base block 1 to the guiding shoulders 12. These jaws are held in position in the sliding blocks by shoulders 28 fitting in grooves 29 in the blocks. These blocks are detachable. Their sides rest upon the top of the base block. Various forms of these clamping jaws may be employed. A modified form is shown in Figure 9.

It will thus be seen that the complete tool is a relatively simple one consisting of a base block, the unitary guiding shoulders, a head block U-shaped in general form, the sliding blocks, the clamping jaws, and the main actuating screw.

In order to form a convenient method of adjusting the sliding blocks and the clamping jaws to a key of predetermined size in order to provide means of adjusting the jaws quickly to the key, I provide an adjusting screw 30. This screw has a squared head 31 upon which is detachably mounted a socket wrench 32 for adjusting the position of it. It carries on its inner end a grooved head 34. On this grooved head is mounted a cup-shaped block 35 carrying a set screw 36 which engages with the inner ends of

the clamping jaws 20. Thus it is possible to move the blocks and jaws relative to the key without moving the tool as a whole.

In case a short shaft is being worked upon as in Figure 4, the shaft being designated 38, I provide an anti-tipping device which is detachable from the tool. This anti-tipping device consists of a sliding anti-tipping block 39. It is guided in upwardly and laterally extending L-shaped guides 40 held in position by screws 41 on the head block 24. This head block is provided with an aperture 42 through which is inserted a sleeve 43 held in position in the block by the set screw 44. This sleeve is internally spaced to carry the screw 45 which is threaded in the carrier block 39 of which the sleeve 43 is an integral part. This screw 45 has a squared head 46^a to receive the socket wrench 32 and adjust it while its other end is provided with a locating point 47 for engagement with the end of the shaft. This carrier block 39 extends downwardly behind the anti-tipping block and base block in an arm 46 and terminates in an eye which has an aperture 48 through which passes the main screw 2 freely. In order that this carrier block and its mechanism may travel with the rest of the tool in predetermined relationship therewith so that as the movement of the tool takes place the anti-tipping device will be held in firm engagement with the end of the shaft 38, a pair of collars 49 and 50 are provided which are threaded upon the main screw 2. One of these collars serves to hold the arm 46 in this predetermined relationship, while the other collar acts as a locknut. These collars are provided with apertures 51 to receive a wrench if that is desired.

The clamping jaws 20 may be further fixed in position on the blocks by the use of screw 52.

In Figure 5, I designate the long shaft such as line shafting 53 and the hub with the pulley 54.

It will be noted in this figure and in Figure 6 the anti-tipping device has been removed as that is not necessary and would be in the way when resting the tool upon a continuous piece of shafting of the character disclosed.

It will be understood that I desire to comprehend within my invention such modifications as may be necessary to adapt it to varying conditions of use.

Having thus fully described my invention, what I claim as new and desire to secure by Letters Patent, is:

1. In a key pulling tool, a base block, spaced converging guiding members, tapered sliding blocks carried thereby, engaging jaws carried by the respective blocks, and means carried by said base block such as a screw adapted to have one end actuated and

- the other end engaging an abutment adjacent the shaft in which the key is located which is engaged between the jaws.
2. In a key pulling tool, a base block, spaced converging guiding members, tapered sliding blocks carried thereby, engaging jaws carried by the respective blocks, means carried by said base block such as a screw adapted to have one end actuated and the other end engaging an abutment adjacent the shaft in which the key is located which is engaged between the jaws, and a head block mounted on said base block, and screws carried on said sliding blocks traveling in apertures on said head block to cooperate in guiding said sliding blocks. 70
3. In a key pulling tool, a base block, spaced converging guiding members, tapered sliding blocks carried thereby, engaging jaws carried by the respective blocks, means carried by said base block such as a screw adapted to have one end actuated and the other end engaging an abutment adjacent the shaft in which the key is located which is engaged between the jaws, a head block mounted on said base block, screws carried on said sliding blocks traveling in apertures on said head block to cooperate in guiding said sliding blocks, and means carried by said head block for adjustably positioning said sliding blocks and jaws in engagement with the key. 80
4. In a key pulling tool, a base block, spaced converging guiding members, tapered sliding blocks carried thereby, engaging jaws carried by the respective blocks, means carried by said base block such as a screw adapted to have one end actuated and the other engaging an abutment adjacent the shaft in which the key is located which is engaged between the jaws, a head block mounted on said base block, screws carried on said sliding blocks traveling in apertures on said head block to cooperate in guiding said sliding blocks, means carried by said head block for adjustably positioning said sliding blocks and jaws in engagement with the key, said means consisting of a screw turning in said head block. 90
5. In a key pulling tool, a base block, a U-shaped supplementary block consisting of a transverse head block and arms having inwardly extending overhanging ledges and guiding surfaces converging towards one another towards the outer ends of said arms, whereby a keystone space is formed between said block and arms, triangular shaped sliding blocks sliding on said inner surfaces of said arms beneath said ledges having parallel inner faces parallel with the major axis of the tool, clamping jaws carried on the respective parallel faces of the sliding blocks, guiding stems reciprocating in the head block carried by the sliding blocks, said stems being parallel with the converging 95
- faces of the arms, and a main actuating screw carried in the base block having one end adapted to actuate the screw and the other end to engage with an abutment on the shaft in which the key is located. 100
6. In a key pulling tool, a base block, a U-shaped supplementary block consisting of a transverse head block and arms having inwardly extending overhanging ledges and guiding surfaces converging towards one another towards the outer ends of said arms, whereby a keystone space is formed between said block and arms, triangular shaped sliding blocks sliding on said inner surfaces of said arms beneath said ledges having parallel inner faces parallel with the major axis of the tool, clamping jaws carried on the respective parallel faces of the sliding blocks, guiding stems reciprocating in the head block carried by the sliding blocks, said stems being parallel with the converging 105
- faces of the arms, and a main actuating screw carried in the base block having one end adapted to actuate the screw and the other end to engage with an abutment on the shaft in which the key is located, and a second screw mounted in the head block having a hub adapted to engage with the clamping jaws to position the jaws in the sliding blocks in clamping engagement with the key. 110
7. In a key pulling tool, a supporting means, jaw carrying means, key clamping jaws, said jaws and the carrying means being so arranged that as they move in one direction the faces will be maintained in parallel relationship and will draw together to engage a key, a master actuating means for moving the block and jaws with a key relative to a shaft, and a separate setting means for initially setting the jaws and blocks in clamping engagement with the key. 115
8. In a key pulling tool, a base block, a U-shaped supplementary block consisting of a transverse head block and arms having inwardly extending overhanging ledges and guiding surfaces converging towards one another towards the outer ends of said arms, whereby a keystone space is formed between said block and arms, triangular shaped sliding blocks sliding on said inner surfaces of said arms beneath said ledges having parallel inner faces parallel with the major axis of the tool, clamping jaws carried on the respective parallel faces of the sliding blocks, guiding stems reciprocating in the head block carried by the sliding blocks, said stems being parallel with the converging 120
- faces of the arms, and a main actuating screw carried in the base block having one end adapted to actuate the screw and the other end to engage with an abutment on the shaft in which the key is located, a second screw mounted in the head block having a hub adapted to engage with the clamping jaws to position the jaws in the sliding blocks 125
- 130

in clamping engagement with the key, and means for preventing the tool from tipping relative to the shaft, means being provided to maintain said anti-tipping means in engagement with the shaft constantly in a predetermined relationship to assist the movement of the tool with the key relative to the shaft.

9. In a key pulling tool, a supporting means, jaw carrying means, key clamping jaws, said jaws and the carrying means being so arranged that as they move in one direction the faces will be maintained in parallel relationship and will draw together to engage a key, a master actuating means for moving the block and jaws with a key relative to a shaft, and a separate setting means for initially setting the jaws and blocks in clamping engagement with the key, and means for preventing the tool from tipping relative to the shaft, means being provided to maintain said anti-tipping means in engagement with the shaft constantly in a predetermined relationship to assist the movement of the tool with the key relative to the shaft.

10. In a tool, a base block, an actuating screw having a head on one end and an actuating head on the other, means carried on the block for engaging a key, means to force said key engaging means into engagement with the key with increasing force as the movement of the block progresses, an anti-tipping device consisting of a transverse block, a depending arm, means on said main actuating screw to maintain the depending arm and block in engagement with the base block despite the movement of the screw, a second screw carried by the anti-tipping block having one end to actuate the screw and the other adapted to engage with the end of a shaft, and a third screw passing through said depending arm and carried by said base block having a head adapted to engage with said clamping jaws to move them upwardly and inwardly with the sliding blocks in engagement with the key.

11. In a key pulling tool, a base block,

an actuating screw having a head on one end and an actuating head on the other, means carried on the block for engaging a key, means to force said key engaging means into engagement with the key with increasing force as the movement of the block progresses, an anti-tipping device consisting of a transverse block, a depending arm, means on said main actuating screw to maintain the depending arm and block in engagement with the base block despite the movement of the screw, a second screw carried by the anti-tipping block having one end to actuate the screw and the other adapted to engage with the end of a shaft, and means on said base block for guiding the anti-tipping block in sliding engagement therewith.

12. In a key pulling tool, a base block, an actuating screw having a head on one end and an actuating head on the other, means carried on the block for engaging a key, means to force said key engaging means into engagement with the key with increasing force as the movement of the block progresses, an anti-tipping device consisting of a transverse block, a depending arm, means on said main actuating screw to maintain the depending arm and block in engagement with the base block despite the movement of the screw, a second screw carried by the anti-tipping block having one end to actuate the screw and the other adapted to engage with the end of a shaft, and a third screw passing through said depending arm and carried by said base block having a head adapted to engage with said clamping jaws to move them upwardly and inwardly with the sliding blocks in engagement with the key.

In testimony whereof, I affix my signature.

MURVIN C. DEIFENDERFER.
